UNITED STATES PATENT OFFICE.

FRANK W. ROLLER, OF EAST ORANGE, NEW JERSEY, ASSIGNOR TO ROLLER-SMITH COMPANY, A CORPORATION OF NEW YORK.

CIRCUIT BREAKER.

Application filed September 24, 1924. Serial No. 739,512.

This application relates to automatic circuit breakers and although shown and described herein in the form of a multi-pole circuit breaker, the invention is equally well adapted as to some features to single-pole breakers. In the particular embodiment described, the invention is shown as applied to a three-pole breaker adapted for the control of the lines of a three-wire circuit. 10 The general object of this invention is to provide a circuit breaker which will be of a simple form of construction and durable and dependable in operation and embody the various features with the attendant advantages hereinafter referred to. 15

One particular object of the invention is to prevent the operator from holding the breaker closed, while an abnormal condition of the circuit exists, or in other words to 20 always permit the opening of the breaker when an overload exists, or other abnormal circuit conditions which may be desirable to safeguard against. A further object of the invention is to insure the immediate opening 25 of the circuit breaker automatically upon the occurrence of a predetermined overload current, and also insure the automatic opening of the breaker upon the occurrence of overload currents less than said 30 predetermined value after the same has continued for a certain length of time, depending upon the magnitude of the current. A further object is to insure the opening of all poles of the breaker when an abnormal 35 condition exists in any one of the circuits. Another object is to insure a quick closing of the circuit breaker contacts with sufficient 40 pressure exerted between the contacts to insure good electrical contact of the switch parts and to also insure the quick opening 45 of the circuit breaker contacts, whether opened manually or automatically. Another object is to provide a simple form of operating and controlling mechanism which will 50 avoid the necessity of using the commonly used toggle mechanism and reduce the number of parts to a minimum. I thereby secure a simple and compact form of construction. Other objects and advantages of my invention 55 will be understood from the following description and accompanying drawings which illustrate a preferred embodiment thereof.

Fig. 1 is a plan view of my improved breaker with the enclosing cover removed;

Fig. 2 is a side view of the same, partly in section, showing the breaker in open position; Fig. 3 is a view similar to Fig. 2 with the parts in engaging position for closing; and Fig. 4 is a similar view showing the 60 circuit breaker in closed position.

The circuit breaker parts are all mounted upon a base 1 of insulating material, which base and parts carried thereby, are removable from a box or casing 2 below the 65 base 1, which casing is adapted to contain oil. The breaker is enclosed at the top by a removable cover not shown in the drawing.

The three-wire incoming leads are shown 70 at the left of the drawings connected to terminal posts 3 which are mounted upon the base 1 and carry at their lower ends the fixed contacts 4. The three yieldable movable contacts are shown at 5 and are respectively carried by three conducting bars 6 which in turn are pivotally mounted in the lower ends of depending brackets 7 secured to the under face of the base 1. The three bars 6 are mechanically connected together 75 by a cross block 8 of insulating material. Secured to one of the bars 6, and preferably the middle bar, is a U-shaped element 9. This element is insulated from its bar 6 and pivotally carries between its upper ends a 80 pair of upwardly extending links 10. Between the upper ends of the links 10 is located a pin or roller 11. From the outer ends of the pin 11 and from the outside of the links 10 extend a pair of links 12 which 85 are in turn pivotally connected to two of the downwardly extending arms of brackets 7. The breaker is biased to open position by the spring effect of the brushes 5, by gravity and also by action of the spring 13 secured at its upper end to the base 1 and at its lower end to an extension 14 from one 90 of the pivoted bars 6. It is evident that when an upward pull is exerted upon the pin 11 the breaker will be closed and held 95 closed, but when the pin 11 is released, the breaker will be thrown to its biased normally 100 open position.

The outgoing leads are shown at the right hand side of the drawings and are connected to three binding posts 15 which are mounted on the base 1 and extend to the under side thereof. From the lower end of each of the outer binding posts 15 extends a bi-metallic 105 thermostatic strip 16, which carries at its 110

inner end a terminal 17 and a plate 18, which plate extends under a plunger 19 which extends freely through the base 1 and which will afterwards be explained. Each of the two plates 18 has its respective plunger 19, one for each of two of the three lines of the circuit. From the two terminals 17 flexible leads 20 extend to and are electrically connected to the lower end of conducting posts 21 which extend upwardly through the base. The upper ends of two posts 21 are electrically connected respectively to a pair of overload coils 22, the other ends of the coils being connected to a pair of conducting posts 23 mounted upon the base 1 and which extend to the under face thereof. From the lower ends of the posts 23 extend a pair of flexible conductors 24 which are respectively connected to the two outer conducting bars 6 of the movable contacts. Thus from the two outer lines the electrical circuit passes from the two outer binding posts 15 through the thermostatic strips 16, then through the overload coils and then to the two outer movable contacts of the breaker respectively. The lower end of the middle binding post 15 is electrically connected directly to the middle conducting bar 6 of the breaker through a flexible lead 25. A back stop 26 of insulating material extends down from the under side of the base and is adapted to engage the extension 14 to limit the open position of the movable contacts.

The operating arm 27 of the breaker is connected to a shaft 27^a which has a bearing in an outer support 27^b and has an inner U-shaped portion 27^c, the inner end of which is pivotally mounted between a pair of supports 27^d fixed to the base. From the inner end of the part 27^c extends an arm 27^e to the right, the end of which arm is adapted to engage the base 1 and serve as a stop for the handle element when thrown to the right. From the inner end of part 27^c another arm 27^f extends to the left which is adapted to engage the base and serve as a stop for the handle element when thrown to the left. The arm 27^f also carries two opposite outwardly extending parts 27^g, at the end of which are connected respectively the operating springs 28. The right hand ends of these springs are connected to the outer ends respectively of pins 29 which in turn are fixed to and carried by a pair of links 30. These links are pivotally mounted at their left hand ends between supports 27^d; and the links are connected together at their right hand ends by a pin 30^a. When the links 30 are caused to move downwardly about their pivotal support, the right hand end of the links will strike against the base which serves as a stop for limiting their movement in one direction. Movement in the opposite direction is limited by the pins 29 engaging a pair of plates 31 fixed to the base and which have

their left hand portions under-cut to serve as a stop for the pins 29. Pivotaly mounted on the links 30 is a controlling element comprising a cross-bar 32 at its upper end, from which downwardly extend at the middle portion a pair of arms 32^a. These arms embrace the links 30, being pivotally connected thereto, and extend downwardly through the base and unite to form a downwardly extending latch 32^b. This latch is adapted to engage the pin 11 and is biased towards the pin 11 by a spring 33 connected between the latch arm 32^b and a support fixed to the under side of the base.

The automatic tripping of this latch and release of the movable switch contacts from the operating mechanism of the breaker is controlled by the overload coils 22. Each overload coil is mounted upon the middle leg 34 of an E-shaped magnet, the three arms 35 of the magnet extending upwardly. On the left hand arm of each magnet is pivotally mounted an armature 35. Secured to the back of each armature is a strip 35^a which has a depending tongue 35^b. When either of the armatures 35 is attracted by its respective magnet, the tongue 35^b will engage the bar 32 forcing it to the left and causing the latch 32^b to be thrown to the right. A triangularly shaped plate 35^c is adjustably secured by screws to the inner end of each armature and is adapted to engage the pivotal support of the armature to serve as a stop to limit the outer position of the armature 35. Secured to the inner end of each armature 35 is a spring 35^d which extends downwardly and is secured at its inner end to the frame of the overload magnet. This spring may be adjustable to the desired tension for normally holding the armature 35 in its outer position. Secured to the inner end of each armature is also a pin 35^e from which depends a rod 36. This rod is threaded at its lower end and carries the previously mentioned plunger 19 which is adjustable in position on the threaded rod 36.

In operation, let us first assume that the breaker is open and the parts in engaging position ready for closing as shown in Fig. 3. In this position the operating handle is at the left which has thrown the outer ends of springs 28 downwardly as shown. When the handle is moved to the right the left hand ends of the operating springs 28 are moved upwardly until, when the line of action passes the pivot of the links 30, the springs cause the inner ends of the links 30 to be thrown upwardly to the position shown in Fig. 4. This upward movement of the links carries the latch arm 32^b therewith and, as this latch is in engagement with pin 11, the movable contacts of the breaker are thrown to closed position as shown in Fig. 4. If an overload exists sufficient to cause either one or both of the armatures 35 to be

attracted, the bar 32 will be pushed to the left and cause the latch 32^b to be thrown out of engagement with the pin 11. This permits the breaker to open even though the operator continues to hold the operating handle in closing position. When the breaker is thus opened automatically the parts will assume the position shown in Fig. 2. In order to again close the breaker the operating handle is thrown to the left which causes the outer ends of the springs 28 to be thrown downwardly across the pivotal support of the links 30 which thereby carries the latch 32^b downwardly to engage the pin 11, the parts then assuming the position shown in Fig. 3. The breaker may now be closed by throwing the operating handle to the right, as previously described, the parts then assuming the position shown in Fig. 4.

Considering now the delayed action overload responsive controlling means, we may assume the breaker to be in closed position shown in Fig. 4. Upon the occurrence of a sufficiently large overload, either one or both of the armatures 35 will be instantly attracted and cause the breaker to be immediately opened automatically. If, however, an overload exists which is not sufficient to instantly attract either one of the armatures 35, the passage of this overload current through either one or both of the thermostatic strips 16 will cause one or both of them to be subjected to an increasing temperature. This of course causes the strip 16 to assume a curved shape and cause its inner free end to be gradually raised and cause the plate 18 to engage and gradually raise the plunger 19. If this assumed overload persists long enough, the raising of plunger 19 will continue and at the same time cause its armature 35 to gradually approach the poles of the overload magnet. When the armature 35 is finally brought to a position near enough to the poles of the magnet to be attracted by the magnet at the value which the overload current then has, it will then cause the breaker to be tripped and opened automatically. Thus, if the overload current is of moderate amount and persists long enough, the circuit breaker will be opened automatically after a predetermined time interval, the time interval depending upon the strength of the overload current passing; and the smaller the overload current the longer will be the time interval. This is due to two causes, first, a small overload current will take a longer time to distort the thermostatic strip and to bring the armature 35 to a position to be attracted by its magnet, and second, the smaller the overload current, the nearer must the armature 35 be brought to the poles of the magnet, before it will be attracted. On the other hand if the overload current is very high, such as may be due to a short circuit condi-

tion, the breaker will be instantly opened, as already explained. The above described automatic spring will, of course, occur when either or both of the armatures is attracted and thus protect all three lines from over-load currents.

As a convenient means for showing whether the breaker is closed or opened, in view of the breaker being enclosed and the position of the handle not being an indication of the position of the circuit breaker contacts, I have provided an indicator 37 which is pivotally supported on the base by an upwardly extending arm 37^a. The indicator is suitably marked such as by the words "Off" and "On" and one or the other of these markings will appear through an opening in the casing according to the position of the circuit breaker contacts. The indicator 37 has an arm 37^b to the end of which is pivotally connected a bar 38 which extends downwardly through the base and is pivotally connected to the outer end of the extension 14. In Fig. 2 the marking "Off" appears through the opening in the casing and it is evident that when the breaker is moved to closed position as shown in Fig. 4 the indicator is thrown to a position so that the marking "On" appears opposite the opening in the casing.

Although I have described this breaker as being controlled by overload, it is evident that the control of the breaker may be made subject to other abnormal controlling conditions by means well understood by those skilled in the art. And although I have shown one particular embodiment of my invention, the same is subject to various modifications without departing from the scope of this invention.

I claim:

1. A circuit breaker comprising a pivoted manually operated element, a second pivoted element, a spring connected between said elements, a movable contact biased to open circuit position, releasable connecting means pivoted to said second element and in releasing contact with said movable contact, and automatic tripping means for releasing said movable contact from said second element upon the occurrence of an abnormal circuit condition.
2. A circuit breaker comprising a pivoted manually operated element, a second pivoted element, a spring connected between said elements, a movable contact, a latch device pivoted to said second element and connecting said second element with said movable contact, and means for automatically releasing said latch device upon the occurrence of an abnormal circuit condition.
3. A circuit breaker comprising a base plate, a manually operated element pivotally mounted thereon, a second element pivotally mounted thereon, a spring connecting

said elements, a movable contact element on the opposite side of said base plate, releasable means extending through said base plate and connected between said second element, and said contact element, and automatic means for disconnecting said releasable means upon the occurrence of an abnormal circuit condition.

4. A circuit breaker comprising a base plate, a manually operated element pivotally mounted on said base plate, a second element pivotally mounted on said base plate, a spring connecting said elements and adapted by movement of said manually operated element in opposite directions to carry the line of action of said spring across the pivot of said second named element, a movable contact element on the opposite side of said base plate, a latch adapted to releasably engage said contact element, said latch being pivotally connected with said second named element and extending through said base plate, and means for automatically releasing said latch from said contact element upon the occurrence of an abnormal circuit condition.

5. A circuit breaker comprising a base plate, a manually movable element pivotally mounted thereon, a second element pivotally mounted thereon, a spring connecting said elements, a plurality of movable contact elements on the opposite side of said base plate, a latch extending through said base plate and releasably connected between said second element and said contact elements, a plurality of controlling coils connected in the circuits of said breaker, said coils having armatures respectively controlled thereby, and each of said armatures being adapted to engage said latch upon the occurrence of an abnormal circuit condition in its respective controlling coil and thereby release said latch from said contact elements.

6. A circuit breaker comprising a base plate, a manually operated element pivotally mounted thereon, a second element pivotally mounted thereon, a spring connecting said elements and adapted by movement of said manual element to have the line of action of the spring carried across the pivotal support of said second element, a plurality of contact elements on the opposite side of said plate, a single latch releasably connecting said contact elements with said second element, a plurality of overload magnets on the side of said base plate opposite from said contact elements and connected respectively in certain of the circuits, and the armatures of said magnets each being adapted to engage said latch and release the same from said second element upon the occurrence of overload current in its respective overload magnet.

7. A circuit breaker comprising a pivoted manually operated element, a second ele-

ment pivotally mounted thereon, a spring connecting said elements and having its line of action adapted to be carried across the pivot of said second element upon movement of said manually operated element for closing said breaker and retaining the same in closed position under normal operating conditions, a controlling magnet having an armature for automatically opening said breaker upon the occurrence of an abnormal circuit condition and thermostatic means for varying the controlling effect of said magnet upon the occurrence of an abnormal circuit condition when continued for a certain time interval.

8. A circuit breaker comprising operating mechanism on one side of said plate for controlling the closing of the breaker, a movable contact element of the breaker mounted on the opposite side of said plate, means comprising a magnet and movable armature for automatically opening said breaker upon the occurrence of an abnormal circuit condition, said means being mounted on the opposite side of said plate from said contact element, and a thermostatic device mounted on the same side of said plate as said contact element for varying the position of said armature in relation to the poles of its magnet when an abnormal circuit condition is continued a certain time interval.

9. A circuit breaker comprising a base plate, a manually operated element pivotally mounted thereon, a second element pivotally mounted thereon, a spring connecting said elements and having its line of action adapted to be carried across the pivot of said second element upon movement of said manually operated element, a movable contact on the opposite side of said plate, releasable means connected between said second element and said contact element and extending through said plate, an overload magnet having a movable armature for automatically releasing said releasable means upon the occurrence of a predetermined overload current, a thermostatic device on the same side of said plate as said contact element, and means controlled by said thermostatic element for varying the position of said armature when the passage of an abnormal current through the breaker is continued for a certain time interval.

10. A circuit breaker comprising a base plate, a manually operated element pivotally mounted thereon, a second element pivotally mounted thereon, a spring connecting said elements and having its line of action adapted to be carried across the pivot of said second element upon movement of said manually operated element, a movable contact on the opposite side of said plate, releasable means connected between said second element and said contact element and

- extending through said plate, an overload magnet having a movable armature for automatically releasing said releasable means upon the occurrence of a predetermined 5 overload current, a thermostatic device on the same side of said plate as said contact element, and a plunger connected to said armature and passing through said plate controlled by said thermostatic element.
- 10 11. A circuit breaker comprising a manually operated element, a second element pivotally mounted thereto, a spring connecting said elements and having its line of action adapted to be carried across the pivot 15 of said second element upon movement of said manually operated element for closing the circuit breaker contacts during which operation energy is stored during the first part of the movement of said manually operated element and later expended to accelerate the rapidity of the closing movement of the circuit breaker contacts, and automatic means, acting independently of said first named means for quickly opening 20 25 the breaker upon the occurrence of an abnormal circuit condition.
12. A circuit breaker comprising a manually operated element, a second element pivotally mounted thereto, a spring connecting 30 said elements and having its line of action adapted to be carried across the pivot
- of said second element upon movement of said manually operated element for opening the circuit breaker contacts during which operation energy is stored during the first 35 part of the movement of said manually operated element and later expended to permit the rapid opening movement of the circuit breaker contacts, and automatic means for controlling the opening of the circuit 40 breaker upon the occurrence of an abnormal circuit condition.
13. A circuit breaker comprising a manually operated element, a second element pivotally mounted thereto, a spring connecting 45 said elements and having its line of action adapted to be carried across the pivot of said second element upon movement of said manually operated element, for closing and opening the circuit breaker contacts during 50 which movements energy is stored during the first part of the movement of said manually operated element and later expended, whereby the rapidity of the movement of the contacts during the closing and opening 55 movements of the circuit breaker contacts respectively is accelerated, and automatic means for controlling the opening of the breaker upon the occurrence of an abnormal circuit condition.

FRANK W. ROLLER.
